(57) **CLAIM**

The ornamental design for an outdoor electric receptacle, as shown and described.

DESCRIPTION

FIG. 1 presents a pictorial view of the first embodiment of my new outdoor electric receptacle design.

FIG. 2 presents a front elevational view of the outdoor electric receptacle illustrated in FIG. 1.

FIG. 3 presents a left side elevational view of the outdoor electric receptacle illustrated in FIG. 1.

FIG. 4 presents a rear elevational view of the outdoor electric receptacle illustrated in FIG. 1.

FIG. 5 presents a top view of the outdoor electric receptacle illustrated in FIG. 1.

FIG. 6 presents a bottom view of the outdoor electric receptacle illustrated in FIG. 1.

FIG. 7 presents a pictorial view of an alternate embodiment of the outdoor electric receptacle illustrated in FIG. 1 showing the outlet covers in a closed position.

FIG. 8 presents a front elevational view of the outdoor electric receptacle illustrated in FIG. 7; and,

FIG. 9 presents a left side elevational view of the outdoor electric receptacle illustrated in FIG. 7.

The right side elevational view of the embodiment shown in FIG. 1 is a reverse image of the view shown in FIG. 3.

The right side elevational view of the alternate embodiment shown in FIG. 7 is a reverse image of the view shown in FIG. 9.

The top and bottom views of the alternate embodiment, shown in FIG. 7 are the same as the respective views shown in FIGS. 5 and 6.

The broken lines in the drawings are for illustrative purposes only and form no part of the claimed design.
